UNITED STATES PATENT OFFICE.

FRANK E. ROBERTSON, OF CLEVELAND, OHIO, ASSIGNOR TO THE P. A. GEIER COMPANY, OF CLEVELAND, OHIO, A CORPORATION OF OHIO.

SUCTION CLEANING APPARATUS.

1,382,548.

Specification of Letters Patent. Patented June 21, 1921.

Application filed July 22, 1916. Serial No. 110,689.

To all whom it may concern:

Be it known that I, FRANK E. ROBERTSON, a citizen of the United States, residing at Cleveland, in the county of Cuyahoga and

5 State of Ohio, have invented certain new and useful Improvements in Suction Cleaning Apparatus, of which the following is a specification.

My invention relates to improvements in 10 suction cleaning apparatus, and, more particularly, to means associated with the suction nozzle thereof, comprising a brush permanently attached thereto and adapted to be actuated into and out of positions of effective operation with respect to said nozzle.

It has been long recognized that apparatus of this type may be most advantageously operated in connection with a brushing or sweeping member and these, ordinarily, have 20 consisted in a brush positioned within the nozzle of the suction cleaner or a separate brush member adapted to be placed upon and removed from the nozzle. The former type somewhat obstructs the nozzle and is 25 inclined to collect dust, while the latter requires a certain amount of time and attention for attaching and removing the brush. Inasmuch as conditions frequently arise for using the suction nozzle alternately with or 30 without the brush, it is quite desirable to construct the brush member so that it may be put into and out of use at the will of the operator. This I have done by means of an 35 actuating mechanism secured at the side of the suction nozzle, which permits the brush to coöperate therewith or withdraws it entirely from use. Preferably, the brush is 40 resiliently mounted and it is associated with adjusting means so that practically the entire volume of air may be drawn through the brush member as it is swept over the carpet, and thereby increases the efficiency of the suction cleaner.

The features of my improvement will be 45 more readily understood by making reference to the accompanying sheet of drawings wherein Figure 1 is a side elevation of a suction cleaning appliance partially broken away and equipped with my improvement. 50 Fig. 2 is a fragmentary rear view as indicated by the line 2—2 and the arrow in Fig. 1. Fig. 3 is a similar view with the outer casing removed for the purpose of showing the actuating mechanism of the brush. Fig. 55 4 is still another fragmentary view showing

the brush and its depressing spring; and Fig. 5 is an enlarged side view of the nozzle and brush, illustrating by dotted lines the extreme operative positions thereof. Throughout the several figures of the drawing I have employed the same character of reference to indicate similar parts.

Referring first to Fig. 1, showing suction cleaning apparatus *a*, my said invention is illustrated applied to the nozzle *b* thereof. 65 This nozzle is removable from the fan chamber and adjustable as to position and height by means of the screw *c'* which acts upon the horizontally pivoted arm mounting the rear wheel *c*. The extremes of operating 70 position for the nozzle are shown by full and dotted lines in Fig. 5. The two lugs *b'* upon the rear of the nozzle are adapted to support the adjustable brush mechanism, comprising the brush member *d*, which is co- 75 extensive with and is positioned closely adjacent to the rear edge of the suction nozzle. This brush member has a lug *d'* and is normally depressed by a bowed spring *d''*, which reacts against the lugs *b'*. An adjusting 80 plate *e* is terminally slotted in its upper portion at *e'* to accommodate the lugs and is provided with a substantially triangular cam opening *e''* for receiving the lug *d'*, positioned rearwardly of the brush member. 85 A face plate *f*, slotted at *f'*, is secured to the lugs *b'* and permits of vertical movement of the lug *d'* within said slot, under the tension of the spring *d''* or the action of the cam opening *e''* provided in the actuating 90 member.

In Fig. 3 the several parts are shown in their position for retracting the brush, in which position the lug *d'* is retained in a slight depression at the right of the cam 95 opening *e''*. Upon moving the adjusting member to the right, however, said lug is disengaged and the spring forces the brush member down, so that said member with its cam opening *e''* assumes the dotted line position shown in said figure. Thus, the bristles of the brush will resiliently bear upon the floor or rug over which the suction cleaner is being operated and materially assist in cleaning the same when the suction cleaner 105 is in operation. By adjusting screw *c'*, however, so that the nozzle of the suction cleaner is tilted downward more sharply, the brush will be slightly retracted against the tension of its spring while the forward edge of 110

the nozzle will be brought into contact with the floor or rug. Under these conditions, the greater portion of the air currents must find entrance to the nozzle through the tufts of the brush member and great efficiency is secured for the suction cleaner with this adjustment.

By moving the adjusting member to the left, as shown in Fig. 2, the brush member is once more retracted so that it is out of engagement with the floor or floor covering and the suction nozzle may be used as such for any desired period, subject to the immediate restoration of the brush to its operative position upon reversing the position of the actuating member. Thus, it will be seen that the brush and nozzle may be conjointly used or not, with the least trouble and effort on the part of the operator. Moreover, when the brush member becomes worn, another may be inserted with very little trouble, while the spring automatically accommodates for considerable wear of the brush and for a certain amount of unevenness of the surface being cleaned.

In practice the spring preferably is tensioned, and the bristles of the brush member are of sufficient stiffness to prevent the rug or carpet from being drawn against the mouth of the suction nozzle when the brush member is protruded. (Fig. 5.) It will be understood that any suitable brush or abrading member may be substituted for the specific brush herein shown, provided it shall serve substantially the same purpose.

Although I have shown and described my invention as applied to the suction nozzle of a portable, electrically driven cleaning appliance; being the preferred form in which I have thus far embodied my said invention, I do not desire to be understood as necessarily limiting its application thereto, and accordingly, I claim, and desire to secure by Letters Patent, the following:—

45 1. The combination with an air-current cleaning nozzle, of a spring tensioned to resist the pressure normally induced by the air, a brushing member normally protruded thereby into positions of coöperation with said nozzle exteriorly of its rear edge, and exteriorly accessible means for actuating said member to hold it in inoperative position, substantially as set forth.

55 2. The combination with an air-current cleaning nozzle, of a brush member exteriorly positioned adjacent to one edge thereof, a spring acting thereon normally to press it resiliently into position of coaction therewith, and an exteriorly accessible cam adjustably mounted on said nozzle adapted to occupy either of two positions and when in one of said positions to retract the brush member out of its operative position, substantially as set forth.

65 3. The combination with an air-current

cleaning nozzle, of a brushing member laterally and exteriorly positioned thereon, a spring resiliently extending said member into operative position and tensioned to resist the normal suction of the nozzle and prevent the rug from sealing the mouth thereof, and means for adjusting the edge of the nozzle opposite the brushing member into close relation with the rug, substantially as set forth.

75 4. The combination with a suction cleaning nozzle, of a bristle-tufted brush member positioned at one edge of said nozzle, a retractive cam-part acting against said brush member, and a spring normally protruding the bristles beyond the lower edge of the nozzle and resiliently engaging them with the surface acted upon, said cam being adapted in one position to retract the brush member into its inoperative position, substantially as set forth.

80 5. The combination with a suction cleaning device having a forwardly positioned cleaning nozzle, of means for angularly adjusting the nozzle about a closely adjacent horizontal axis, a brush member positioned adjacent to one edge of the nozzle, an adjusting cam-part acting against said brush member, and a spring acting on said brush member normally to protrude the brush member beyond said edge and resiliently hold it in operative position with respect to said nozzle, said cam being adapted in one position to retract the brush member into its inoperative position, substantially as set forth.

85 6. The combination with an elongated air-current cleaning nozzle, of means for abruptly tilting it along its horizontal axis to bring one edge normally into substantial engagement with the cleaned surface and for retaining it in tilted position, a brush member coextensive with and positioned adjacent to and below its opposite edge, and spring means for pressing the brush against the surface to be cleaned, whereby said brush is adapted to yield upwardly as it contacts with said surface, substantially as set forth.

90 7. The combination with an elongated air-current cleaning nozzle, of means for abruptly tilting it substantially along its horizontal axis to bring one edge closely adjacent to the cleaned surface, a resiliently mounted brush member coextensive with and positioned exteriorly adjacent to and below its opposite edge, and a retracting member adapted to withdraw said brush member from its extended position, substantially as set forth.

95 8. In apparatus of the class described, the combination with the brush member mounted for vertical adjustment, of a tensioned spring normally extending said brush member into operative position, and a movable cam-plate mounted on said nozzle opera-

tively engaging the brush member and adapted in one position to retract and hold it in inoperative position, substantially as set forth.

5 9. The combination with a suction cleaning device having an elongated floor-cleaning nozzle, of an elongated brush member adjustably positioned adjacent to one edge thereof, a tensioned spring resistant to the
10 pressure occasioned by the air and normally protruding the bristles thereof beyond said edge and an accessible cam engaging said brush member and adapted in one position to retract it into inoperative position with
15 respect to said nozzle, substantially as set forth.

10 10. The combination with a suction-cleaning nozzle, of an adjustable brush member coöperatively associated with one edge
20 thereof and mounted for upward movement into inoperative position, a spring normally protruding said brush member for such co-operation, and a detent adapted to be actuated into engagement with the brush member
25 for tensioning the spring and holding said

brush member in its inoperative position with respect to the edge of the nozzle, substantially as set forth.

11. The combination with a suction-cleaning nozzle, of a brush member associated 30 and coextensive with one edge thereof, a spring acting normally to protrude the bristles of said brush member below said edge, a transversely movable plate mounted on said nozzle accessible exteriorly of the 35 device and having upper and lower bearing faces operatively associated with and controlling the position of the brush member, adapted to retract and hold it in inoperative position above the edge of the nozzle or alternatively release it for the resilient protrusion thereof by the spring, substantially as set forth.

In testimony whereof I do now affix my signature in the presence of two witnesses. 45
